MACHINE GUN CRADLE STRUCTURE

John C. Trotter, Buffalo, N. Y., assignor to Bell Aircraft Corporation, Buffalo, N. Y., a corporation of New York

Application April 10, 1940, Serial No. 328,989

1 Claim. (Cl. 89—37)

In general, this invention relates to mounts for machine guns adapted to be used in aircraft, and more particularly to a mount provided with a recoil dampening device, non-moving sight and trigger construction.

Of course, numerous mounts for machine guns adapted to be used in airplanes or the like have been used, but most of these mounts have possessed undesirable features. Among other disadvantageous characteristics is the failure of the mounts to provide any means whereby a sight can be supported against vibration, etc. In addition, the mounts have been rather large which of course is a bad feature since space in an airplane is quite limited. Furthermore, the large size of the mounts makes operation of the guns by the gunner somewhat difficult. Moreover, as far as I am aware no mount has been used in which the recoil control device is so disposed that it can fit under the forward portion of the gun thus conserving space.

An object of this invention is to provide a mount or cradle for machine guns which does not possess the undesirable characteristics of mounts heretofore used.

Another object of this invention is to provide a mount for machine guns which carries a sight, such as a telescopic sight which will not be subject to shock, vibrations, etc.

A still further object of my invention is to provide a mount or cradle for machine guns that carries a recoil compensating device which fits snugly under the gun casing and which will readily compensate for the recoil of the gun.

And yet another object of my invention is to provide a device for attaching a machine gun mount in the fuselage or the like of an airplane which will permit the gun to fire through a 90° arc either above or below the horizontal.

In order to achieve the foregoing and further objects, the invention broadly comprises providing a light weight mount that can be attached in the airplane for swiveling movement and which is so mounted that the gun can be fired through an arc at least 90° above or below the horizontal. The mount carries a single recoil chamber at the forward end thereof which fits snugly under the gun casing, thus saving space and weight. In addition, the provision of a single recoil chamber possesses certain advantageous features over the employment of two or more such chambers since it will prevent any danger of unbalance so to speak between the respective recoil control devices.

Moreover, there is associated with the cradle

5 a support member which is adapted to carry a sight such as, a telescopic sight, and as the sight is supported by the cradle, there can be no movement of the sight upon firing of the gun and the advantage of such construction will be readily appreciated.

In the drawings in which the same numerals indicate the same or similar parts:

Figure 1 is a side elevational view of my novel 10 cradle for machine guns.

Figure 2 is a top plan view of the construction shown in Figure 1.

Figure 3 is a sectional view taken along the 15 line 3—3 of Figure 1 looking in the direction of the arrows.

Figure 4 is a sectional view taken along the line 4—4 of Figure 1 looking in the direction of the arrows.

In the drawings, and more particularly Figure 20 1, there is shown a machine gun 1 supported by a light weight cradle designated generally 2. The cradle 2 supports handles H, recoil control device R, firing trigger T and sight mount S.

The cradle 2 comprises a pair of parallel tubes 25 like members 3 and a slide track casting 4 is attached to the rear end of each tube 3 and is provided with an elongated aperture 5. A bolt 6 carrying a slide block 7 is mounted in each slot 5 for rearward and forward movement. The 30 inner end of each bolt is attached to the machine gun casing.

Secured to the rear portion of each track casting 4 is a tubular member 8 and the outer ends of each member 8 are joined to a second tubular 35 member 9 which extends at right angles to the members 8. A vertical portion 10 is integrally formed with each end of the member 9 and a hand grip 11 is fitted over each vertical member 10. It will be manifest that the hand grips 11 40 and their associated parts form the handles H and are an integral portion of the cradle 2.

In Figures 2 and 4, it will be seen that each tubular member 3 projects through a bracket 12 and each bracket is connected by a transverse 45 support 13. A yoke 14 is pivotally attached at its upper ends as at 15 to the brackets 12 to permit the cradle to have arcuate movement. The lower end of the yoke 14 carries a spindle 16 that is adapted to be fitted into a socket within 50 the body of the plane to permit the cradle to have swiveling movement. When the yoke is mounted in the fuselage in the position shown by the full lines, the gun 1 may be fired through a 90° arc above the horizontal. On the other hand, by positioning the yoke in the manner

shown by the dot-dash lines of Figure 1, the gun can fire through a 90° arc below the horizontal. Consequently, with this simple arrangement, it is possible for the gun to be fired through relatively large angles either above or below the horizontal.

In Figures 1 and 3, it can be seen that the recoil control device R comprises a dampening chamber 17 that is positioned between the parallel tubes 3 at their forward ends and fits rather snugly beneath the casing of the machine gun 1. The construction and operation of the control chamber 17 has been specifically shown and described in my co-pending application, Serial No. 314,542 filed January 18, 1940, now Patent No. 2,309,807, which issued February 2, 1943.

It will be noted that the outer end of the chamber 17 is formed with a lateral support 18 that carries a cup 19 at each end. Each cup 19 fits over the open end of the tubes 3.

As the recoil cylinder 17 is of the hydraulic type it carries a piston rod 20 formed with an eyelet 21 at its outer end. A bolt 22 extends through the eyelet 21 and through apertures formed in the lower end of arms 23 of a mounting bracket construction 24. Spacers 25 are interposed between the eyelet 21 and the arms 23. The opposite or upper ends of the arms 23 are secured to the fore portion of the machine gun casing as indicated at 26. It will be readily appreciated therefore in view of the above description that the machine gun 1, by virtue of its attachment to the cradle 2, is free to have a forward and rearward movement in the cradle upon firing of the gun.

It should be stressed at this time that by employing but a single recoil control chamber which fits snugly beneath the gun casing, considerable space and weight is saved. In addition, it has been determined that when two or more recoil chambers are used there is always the chance that the respective chambers may become unbalanced, but by employing but a single chamber this danger is overcome.

As I pointed out above, an important feature of this invention is the provision of a mount for a sight. In Figure 4, it will be noted that one of the brackets 12 is formed with a vertical extension 30. Attached to the extension as indicated at 31 is a horizontally projecting member 32 which is curved at its rear end as shown at 33 and is attached to the upper portion of one of the grips 11. Secured to the horizontal portion 32 by screws 34 is clamp 35 in which is mounted a telescopic sight 36. The position of the sight 36 is maintained by screws 37. Internal windage and elevation reticles of the sight are adjusted by means of screws 38.

It will be seen that the sight 36 is not subject

to any shock or vibration since its support 35 is carried by the cradle 1 and is not attached in any way to the gun mechanism itself.

The gun assembly is also provided with a firing mechanism, generally designated by the letter T. This firing mechanism T includes a lever 50 mounted adjacent one of the handles 11 which is connected by a suitable linkage 51 to a pivoted firing trigger 52. When it is desired to fire machine gun 1, the lever 50 is moved rearwardly about its pivot. This action is communicated by the linkage 51 to the trigger 52.

From the foregoing description, it will readily be appreciated that the present invention provides a light weight cradle to be used with machine guns mounted in aircraft that in addition to having associated therewith a highly effective recoil control device also carries a novel sight mount and firing trigger mechanism. The recoil control device is so arranged that it will occupy a minimum of space and increase the weight of the cradle and gun very little. Furthermore, the provision of a single recoil chamber prevents any danger of unbalance which would be present in recoil control devices possessing two or more dampening cylinders. By having the sight carried by the supporting cradle rather than the gun itself, the sight will not be subject to any vibration, shock or the like.

The construction is relatively simple in construction and can be cheaply and easily manufactured.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claim.

I claim:

A machine gun mount comprising a cradle for a gun, having side portions and means in each portion for slidably mounting a gun for movement relative to the cradle upon recoil of the gun, a handle for the gun secured to the rear end of the cradle, a means for sighting the gun, and means supported wholly by the cradle for supporting said sighting means whereby the sighting means remains stationary during the recoil of the gun, said supporting means including a bracket mounted on one of the said side portions which forms the cradle, a bridge member rigidly attached to said bracket and a handle of the gun, and a clamp rigidly mounted on said bridge member to which the sighting means is secured.

JOHN C. TROTTER.
